UNITED STATES PATENT OFFICE.

EDWARD COPE, OF NOTTINGHAM, ENGLAND.

DESIGN FOR A LACE FABRIC.

SPECIFICATION forming part of Design No. 22,281, dated March 14, 1893.

Application filed December 19, 1892. Serial No. 455,703. Term of patent 14 years.

To all whom it may concern:

Be it known that I, EDWARD COPE, a subject of the Queen of Great Britain, residing at Chilwell Hall, Nottingham, England, have invented and produced a new and original Design for a Lace Fabric, of which the following is a specification, reference being had to the accompanying drawing, which shows a piece of lace fabric having my design.

The leading feature of my design consists of a lace fabric showing a series of parallel, longitudinal bars arranged equal distances apart, having transverse, closely-arranged lines or ribs, said longitudinal bars being interrupted at intervals by transverse strips having a plain pattern.

In the accompanying drawing—A indicates

the longitudinal, parallel bars composed of transverse lines or ribs *a*, lying closely adjacent and substantially parallel with each other.

a' indicates the spaces between the longitudinal bars.

B indicates the transverse interrupting strips, wherein the pattern is plain. 25

I claim—

The design for a lace fabric herein shown and described.

EDWARD COPE.
